(54) **STOVES, ANTHRACITE COAL**

(76) Inventor: **Adrian Jones**

Adrian James Hartford C.
Letters Patent.

The Subject referred to in these Letters Patent and making part of the same containing a description in the words of himself of his improvement in the Stove for burning Anthracite or hard coal.

To all whom these presents shall come Greeting

To be it known that I, Adrian James of Hartford in the County of Hartford and State of Connecticut, have invented a new and useful improvement in Stoves for burning Anthracite or hard coal, and the following is a full and exact description of the construction and operation of the said Stove as improved by me and which may be denominated a return draft Stove. Take a common upright cylindrical Sheet Iron Stove of any convenient size and height according to the space to be warmed. For general use say for a more definite description take one constructed as follows. One Cylinder twelve inches in diameter and twenty eight inches high, one six inches in diameter and eighteen inches high, and one six inches in diameter and twelve inches high, and these three sizes being placed on each other the largest on the hearth of the stove or at the bottom and the smallest on the top may be called the first, second and third, Stoves. Not being immaterial however except for beauty whether it is of this form or of the same size from the bottom to the top. Place within the first or lower story a second or inner Cylinder ten inches in diameter of the same length with the outer one, and coming in contact with it on the front or outer side, thereby leaving a space between the two cylinders opposite the door of about two inches which space will of course diminish in its sectional area until it terminates in a point on each side where the two cylinders come in contact. The

top of the inner cylinder should then be pared or sloped off from the back of it to the centre of its circumference on each side at an angle of not less than ninety degrees. The portion of the inner cylinder so sloped should be concave with a cap or roof the front of which will be a straight line and should be extended each way in a line to the outer cylinder.

A small space will still remain open at the top between the two cylinders from the points of said cap or roof at each end of the front where said cylinders come in contact. This opening must be closed with a piece of sheet iron or other suitable metal connected to both the inner and outer cylinders and to the ends of said cap or roof so as in conjunction with the partition hereof to be described to cut off all communication between the inner cylinder and the space back of it between the two cylinders except over the top of said partition.

To the front or straight edge of said cap or roof is to be attached and secured a piece of sheet iron extending up and through the second and third stories of said stove to within about three inches of the top which is also to be fastened to the stove on each side of it and will thus form a perpendicular partition dividing the inside of said stove from said cap or roof into two equal parts to the height of said partition. The grate and fire brick are to be placed in the inner cylinder and there may be two doors both which must be cut through the two cylinders where they come in contact. The upper for supplying coal, the lower for draft and if a heated grate is used to allow this fire brick an opening for the smoke pipe should be cut through the outer cylinder only and on the back of it say ten inches from the hearth or bottom of the cylinder will it have found it beneficial to place a piece of sheet iron ^{horizontally} between the two cylinders immediately above the opening for the smoke pipe in such a way as nearly to close up the whole space between the two cylinders for a distance of not less than twice the diameter of the smoke pipe. By this means all the heated air which meets of course

in front of the partitions - fire occurs and descend behind it and before
such two cylinders is drawn as near as possible to the bottom of this
fire before it escapes through the aforesaid pipe.

One opening should then be made through the inner cylinder
on the back of it between the grate and the partitions or bottom
of the fire for the dust and light ashes to pass off into the smoke
pipes where the fire is agitated or stirred. other openings may be
six inches in length by four in width and should be tightly
closed by a clumper except when the fire is agitated to restrain
the ashes from the coal. The clumper may be attached to a
wire passing horizontally through the outer cylinder beneath the
smoke pipe and at right angles therewith, or by a wire pass-
ing perpendicular through the space between the two cylinders
coming out behind the second story of the stove. This pipe
when placed on a cast iron heating flange at the external appearance
of a common upright cylindrical chimney flues except the
location of the pipes and this may be varied for convenience purposes.
The above description corresponds with the stove as used by me
but the dimensions of the stove and the corresponding pipes may
be indefinitely varied - this stove may also be square, elliptical,
hexagonal or any other form in its body section as well as
cylindrical and may be made of cast as well as sheet iron.

To prevent my improvement, among other things, the outer
cylinder of the stove is bounded from that interior part which
always destroys the stove and frequently the material of the stove.
The heat is also distributed without the stove for a long period
and so diffused around the outer cylinder as nearly to expand
itself before the current reaches the smoke pipe and therefore
does any great length of pipe wholly unnecessary.

The opening for the dust and light ashes, being so intimately
connected with the principal draft of the stove through the smoke
pipes, they are effectively carried off and from the location of
the pipes it may be inserted into any common pipe flue with

but little expense or inconvenience. — I do not claim as my invention the above described Stove or any of its parts (taken singly) or the materials of which they are composed. But I do claim the combination of the inner cylinders and partitions (together with the mode of bringing the heated air into the bottom of the cylinders before it passes off) with the common stove as heretofore used by the public.

Signed at Hartford Conn. this 1st day of January 1836
